UNITED STATES PATENT OFFICE.

MARIE TANNER, OF PORTLAND, OREGON.

HAT-SECURING MEANS.

1,276,828.

Specification of Letters Patent. Patented Aug. 27, 1918.

Application filed March 23, 1917, Serial No. 156,809. Renewed July 17, 1918. Serial No. 245,406.

To all whom it may concern:

Be it known that I, MARIE TANNER, a citizen of the Republic of Switzerland, resident of Portland, county of Multnomah, and 5 State of Oregon, have invented certain new and useful Improvements in Hat-Securing Means, of which the following is a specification.

This invention relates to improvements in 10 hat fastening means, and particularly to types worn by ladies in which the hats are engaged with the hair of the head.

The principal object of the invention is to 15 provide means which may be applied to hats of the ordinary style and fashion, which are adapted to be engaged or disengaged with the hair of the wearer so that the hat is held firmly and securely the application being made with entire ease and 20 facility.

A second object is to provide such means 25 which may be applied at any desired time to a hat as indicated and which are inexpensive to manufacture, durable in their nature, and easy to manipulate.

These and other like objects are attained 30 by the novel construction and combination of parts hereafter described and shown in the accompanying drawings, forming a material part of this disclosure, and in which:—

Figure 1 is a perspective view looking from the underside of an ordinary hat.

Fig. 2 is a perspective view showing the 35 device in its preferred form.

Fig. 3 is a transverse sectional view taken on line 3—3 of Fig. 2.

Fig. 4 is a top plan view of the fastener, and

Fig. 5 is an enlarged fragmental sectional view showing the relation of parts.

Fig. 1 shows an ordinary hat, the same being composed of a brim 10, crown 11, and top 12. Obviously two or more of the fasteners may be used as desired, the same consisting of a comb-like plate comprised of flexible material having a rigid bar portion 15, from which extend a plurality of teeth 16, the same being relatively sharp or pointed at their lower end and having between them spaces 17 to receive the hair in the manner of an ordinary comb.

Formed with the bar 15 is a projection 18, containing a single aperture 19 in which the ball of an operator's finger may be 55 pressed in raising or lowering the comb element. The two outermost teeth 20 of the comb are made relatively wider than those therebetween and contain an open longitudinal slot 21 through which passes a transverse bar 25 provided with raised, hook-shaped lugs 26 adapted to engage with the beveled edge 22 of the outer tooth element 23.

The outer ends 27 of the rigid bar 25 are 65 offset and rounded, the same being adapted to be secured to the crown of the hat through sewing or like means in passing through the perforations 28, as best shown in Fig. 1.

From the foregoing, it will be seen that 70 the device is positively attached in the crown of the hat in such manner as to be partially concealed from observation when in a raised position and is capable of being 75 put into use by raising or lowering the comb element with respect to the bar 25 rigid with the interior of the hat.

It will also be evident that different curvatures may be given the comb 15 by reason 80 of engaging the lugs 26 with respect to the bevel edges 22 of the comb structure.

In operation, the bar or bars 25 having been secured in the desired position within the hat, together with the attached comb, two or more of which may be used as desired, depending somewhat upon the shape of the hat, the head of the wearer, and in the manner of which the hair is dressed, the extending end of the comb teeth are pushed up so as to engage with the hair, 90 whereupon the hat will be held firmly in position without the use of pins or other securing means.

When it is desired to release the hat, the comb teeth are drawn down, freeing the 95 hair, and allowing the hat to be removed.

Having thus described my invention, what I claim as new, and desire to secure by Letters Patent, is:—

1. A hat fastener comprising a flexible 100 plate provided with a plurality of teeth extending in one direction, the outermost teeth being of increased width, and having a longitudinal slot therethrough, a flexible bar

extending through the mentioned slot in the end teeth, and hooked lugs formed with said bar contiguous to its ends adapted to engage with said end teeth whereby said comb plate may be adjusted in a secured position.

2. A hat fastener comprising a flexible plate having a pair of widely disposed slotted elements formed upon each of its ends, a plurality of comb teeth formed with

said plate between said end elements, beveled edges formed upon the exterior of said end elements, a flexible bar passing through the mentioned slots, and a plurality of hook shaped lugs formed with said flexible bar adapted to engage with said beveled edges. 10 15

In testimony whereof I have affixed my signature this ninth day of March, 1917.

MARIE TANNER.

Copies of this patent may be obtained for five cents each, by addressing the "Commissioner of Patents, Washington, D. C."
